COLLAPSIBLE BRUSH

William W. Donee, Venice, Calif.

Application October 10, 1955, Serial No. 539,323

10 Claims. (Cl. 15—203)

This invention has to do with collapsible brushes.

An object of the invention is to provide a novel and improved collapsible brush in which bristle-carrying portions are mounted to collapse for housing within the case portion when not in use.

Another object is to provide such a collapsible brush of simple construction which can be readily manipulated by means of a single control element to extend the bristle-carrying portions into position for use and to retract such portions into the case as desired.

A further object is to provide a novel device of the type indicated in which the bristle-carrying elements are expandable and contractable laterally and in which these elements, when contracted, are movable longitudinally into and out of the case portion of the device.

Still another object is to provide a collapsible brush having a case which is suitable as a handle when the brush portion of the device is extended and expanded for use.

A further object is to provide a collapsible brush in which all of the parts are connected together thereby obviating the possibility of any part being misplaced.

Still another object is to provide a collapsible brush which lends itself to mass production methods.

These and other objects will be apparent from the drawings and the following description. Referring to the drawings:

Fig. 1 is a perspective view of a form of brush embodying the invention shown in expanded position for use;

Fig. 2 is a perspective view of the same device in collapsed and retracted position;

Fig. 3 is a plan view of the device with the bristle-carrying elements extended from the case but collapsed laterally;

Fig. 4 is a sectional view on line 4—4 of Fig. 1; Figs. 5 and 6 are sectional views on line 5—5 and 6—6, respectively, of Fig. 2;

Fig. 6A is an enlarged fragmentary sectional view on line 6A—6A of Fig. 6;

Fig. 6B is a plan view of the control element;

Fig. 7 is a perspective view of another form of the invention with the device extended and expanded for use;

Fig. 8 is a view in perspective of the device of Fig. 7 in retracted and collapsed position;

Fig. 9 is a plan view showing the bristle-carrying elements extended but laterally collapsed;

Fig. 10 is a sectional view on line 10—10 of Fig. 7; and

Figs. 11 and 12 are sectional views on lines 11—11 and 12—12, respectively, of Fig. 8.

More particularly describing the invention, referring first to Figs. 1—6, 11 generally indicates the case of a device embodying my invention, and 12 generally designates the brush assembly. The brush assembly includes a central bar 14 having an enlarged inner end portion 15 of T-shape in cross section and having a pair of laterally extending projections or wings 15' which are slidably received in longitudinal channels 16 formed in the sides of the case.

2

The case itself may be formed of two pieces, indicated by 11A and 11B, and these united by any suitable means. The aforementioned channels 16 are defined by the upper wall 17, side wall 18, and a shelf 19 of each portion of the case. With this construction it will be apparent that the central bar 14 is telescopically mounted with reference to the case.

On each side of the central bar I provide an outer bar 20. The central and outer bars carry suitable bristles 21 which are mounted in any conventional manner. The outer bars are connected pivotally to the center bar by links 22 and 23. Link 22 is pivotally secured at 24 to the outer end of the central bar and at 25 to the outer ends of the outer bars. The inner link 23 is pivotally connected at point 26 to the outer bars and is rotatably connected to the central bar 14 by a control element designated 28, the link 23 being received within an opening 29 extending from side to side through the inner end portion of the central bar.

The control element includes an elongated handle portion 30 and a shaft comprised of an upper portion 32 (Figs. 6 and 6B) elongated in the same direction as the handle, a next adjacent cylindrical section 33, a non-circular section 34 shown as square in cross section, and 25 a peripherally grooved cylindrical end portion 35. The portion 32 of the shaft, when turned longitudinally of the case as in Fig. 2, is slidably received in a longitudinally extending slot 37 of the case. This slot is enlarged at 37' to enable the control element to be turned as shown 30 in Fig. 1. The section 32 is partially received in a circular recess or counterbore 38 (Fig. 6A) above a bore 39 which receives section 33 of the shaft. The bottom of the recess is provided with two surfaces 40 which are inclined downwardly in a counterclockwise direction for 35 a purpose which will later appear. Inwardly of these is a second or inner counterbore 41. The square section 34 of the shaft is slidably received in a correspondingly shaped hole 43 in inner link 23. The end portion 35 is received in a bore 44. An L-shaped leaf spring 47 mounted on the inner end of the central bar yieldably 40 anchors the control element, the spring having a bifurcated end 48 which straddles the lower end of the shaft, fitting the groove therein.

With the control element in the position of Fig. 2, the 45 brush assembly parts are retracted laterally and telescoped within the case. By moving the control element to the outer end of the slot 37 and then turning the same about 50° in a counterclockwise direction, the bristle-carrying bars are first extended from the case and subsequently expanded laterally from the position of Fig. 5 to that of Fig. 1. When the control element is in the position of Figs. 2 and 6, the lower surface of the section 32 is supported upon the high portions of the inclined surfaces 40. However, when the control element is turned it rides down the surfaces 40 under the influence of spring 47 to the position of Fig. 4, the spring and surfaces 40 serving to releasably hold the control lever in this position. It should be noted that case section 11A is cut away at 50 to provide clearance for the brush assembly during lateral expansion thereof. The brush assembly may be returned to the case by rotating the control element clockwise about 50° and moving it back to its original position.

Referring to Figs. 7—12, I show an alternate form of the invention wherein numeral 60 generally indicates the case and 61 generally indicates the brush assembly. The case 60 is generally similar to the one previously described in that it is formed of similar or complementary sections 60A and 60B which may be joined together by any conventional means. The case is formed to provide the lateral channels 64 which receive the wing portions 65 formed on the inner end section 66 of a central bar design-

nated generally by 67. The outer portion 68 of the bar carries a row or rows of bristles 70 as do outer bars 71. In this form of the invention the outer bars are connected to the central bar at each end by a pair of links, levers or arms. Links, designated 72 and 72', are pivotally connected at 73 to the outer bars and pivotally connected at 74 to the central bar. These links or arms are provided with interengaging means in the form of meshing gear teeth 75 so that movement of one causes corresponding movement of the other.

At their inner ends the bars are connected by links, levers or arms 76 and 77. These are pivotally secured at 78 to the outer bars, respectively, and are pivotally mounted upon the inner bar by means of a pin 79 which extends through the parts and through a control element or knob 80. The control element 80 has a slotted lower end portion 81 which fits over a flat-sided projection 82 formed on the arm 76 whereby rotative movement of the control lever is transmitted to the link or arm 76. The control element has an elongated section 84 which is received in a slot 85, 85' in the upper wall of the case. At its forward end the case has a box-like portion 88 which houses a V-shaped spring 90.

The case is provided with shields 91 supported by hinges 92. Each shield also has a flat spring 93 which is secured to the shield at 94 and normally lies flat along the inner side of the case. When the brush assembly is within the case, as in Fig. 8, the outer bars 71 lie against the springs 93, thereby serving to hold the shields in line with the sides of the case. When the outer bars 71 are expanded from the full-line position of Fig. 9 to the broken-line position thereof, the shields yield to the outward movement of the links 76 and 77 and swing outwardly as shown in broken lines and as shown in Fig. 7. When the shields swing out the inner ends of springs 93 swing inward to engage the inner end portion of central bar 67 to yieldably limit outward swing movement of the shields.

In the operation of the device, assuming the parts are in the position shown in Fig. 8, the brush assembly 61 may be moved to the position of Fig. 9 by moving control element 80 to the enlarged end portion 75' of slot 75. The brush assembly can then be expanded to the position of Fig. 7 by turning the handle 90° in a counterclockwise direction. The shields 91 swing out to permit this, thereby obviating the necessity of having an unduly long case. Spring 90 serves to yieldably hold the control element in this position by reason of bearing against the flat side of portion 84 of the control element which is elongated in the direction of the outermost or handle portion of the control element until it is desired to return the parts to their original collapsed and retracted position by return movement of the control element. It will be apparent that in both forms of the invention, with the brush assembly extended, the case can be used as a handle. It will also be apparent that the links 22, 23 of Figs. 1-6, and the links 72, 72', 76 and 77 of Figs. 7-12 may be termed a partially rotatable linkage means connecting the bars.

While I have shown three bristle-carrying bars, I contemplate that more or less than this number can be used without departing from the invention. Also, various other modifications and changes can be made therein without departing from the invention, the scope of which is indicated by the following claims.

I claim:

1. A collapsible brush, comprising a case with an opening at one end, a central bristle-carrying bar mounted in said case for telescopic movement therewith, an outer bristle-carrying bar on each side of said central bar, a link at each end of said central bar pivotally connected thereto at the midpoint of the link, pivotal connection means between the ends of each link and the adjacent ends respectively of said outer bars, said links being sufficiently long, when disposed normal to

said central bar, to space said outer bars laterally of said central bar, said bars being receivable in said case when said outer bars are collapsed to lie adjacent said central bar.

5 2. A collapsible brush, comprising a case with an opening at one end, a central bristle-carrying bar mounted in said case for telescopic movement therewith, an outer, bristle-carrying bar on each side of said central bar, a link at each end of said central bar pivotally connected thereto, pivotal connection means between the end of each link and an adjacent end of an outer bar, said links being sufficiently long, when disposed normal to said central bar, to space said outer bars laterally of said central bar, said bars being receivable in said case when said outer bars are collapsed to lie adjacent said central bar, a control lever mounted on one said link located at the inner end of said bars for pivoting said link whereby to expand or contract said outer bars laterally of said central bar.

10 3. A collapsible brush as set forth in claim 2 in which said case is provided with a longitudinal slot and in which said control lever projects through said slot.

15 4. A collapsible brush comprising a case, a brush assembly including a plurality of bristle-carrying bars and a partially rotatable linkage means mounting the bars for lateral expansion and contraction thereof, said brush assembly being receivable in the case when contracted and being slidable in the case for telescopic movement therewith, and a control lever carried by said brush assembly and non-rotatably engaging said linkage means operable, when moved longitudinally of the case, to move said brush assembly relative to the case and operable, when rotated, to rotate said linkage means whereby to expand or contract said assembly laterally.

20 5. A collapsible brush as set forth in claim 4 in which said case is provided with a slot extending longitudinally of the case and in which said lever projects through said slot.

25 6. A collapsible brush, comprising a case with an opening at one end, a central bristle-carrying bar, laterally projecting wings at the inner end of said bar, means in the case forming a guide channel on each side thereof slidably receiving the respective wings of said bar whereby to mount said bar for telescopic movement relative to the case, an outer bristle-carrying bar on each side of said central bar, and means joining said outer bars to said central bar for adjusted lateral movement toward and away from said central bar, said central and outer bars being receivable in said case when said outer bars are collapsed to lie adjacent said central bar.

30 7. A collapsible brush as set forth in claim 6 in which the means joining said outer bars to said central bar comprises a link at each end of said central bar pivotally secured thereto, and means pivotally securing the ends of said links to the ends of said outer bars.

35 8. A collapsible brush, comprising a case with an opening at one end, a central bristle-carrying bar, laterally projecting wings at the inner end of said bar, means in the case forming a guide channel on each side thereof slidably receiving the respective wings of said bar whereby to mount said bar for telescopic movement relative to the case, interengaging means on said case and said bar limiting movement of said bar relative to said case, an outer bristle-carrying bar on each side of said central bar, a link at each end of said central bar pivotally connected thereto at the mid point of the link, pivotal connection means between the ends of each link and the adjacent ends respectively of said outer bars, said links being sufficiently long, when disposed normal to

40 said central bar, to space said outer bars laterally of said central bar, said bars being receivable in said case when said outer bars are collapsed to lie adjacent said central bar, a control lever mounted on the link located at the inner end of said bars for pivoting said link whereby to expand or contract said outer bars laterally of said

central bar, said control lever being non-rotatively mounted with respect to the link in which it is mounted.

9. A collapsible brush, comprising a case with an opening at one end and having a longitudinal slot, a central bristle-carrying bar having laterally projecting wings at its inner end, said case being formed to provide opposing guide channels slidably receiving said wings, an outer bristle-carrying bar on each side of said central bar, an outer link pivotally connected at its midpoint to the outer end of said central bar and at its outer ends to the outer ends of each of said outer bars, an inner link pivotally connected at its midpoint to the outer end of said central bar and at its outer ends to the inner ends of said outer bars, said links being of equal length, and a control element pivotally mounted in the inner end portion of said central bar and passing through said inner link, said control element serving to pivotally connect said inner link to the inner end portion of said central bar, interengaging means on said control element and said inner link preventing relative rotation of said inner link and said control element whereby rotation of said control element results in rotation of said inner link, said control element projecting through the slot in said case.

10. In a collapsible brush having a case, a brush as-

sembly telescopically mounted in said case comprising a central bristle-carrying bar, a pair of outer bristle-carrying bars positioned one on each side of said central bar, a first pair of arms each pivotally mounted at one end at the outer end of said central bar, means pivotally connecting the other end of each arm to the end of one outer bar, a second pair of arms each pivotally mounted at one end at the inner end of said central bar, means pivotally connecting the other end of each arm of said second pair of arms to the inner end of one outer bar, a control element on one of the arms of said pairs of arms for pivoting the same, and interengaging means on the arms of one of said pairs of arms for transmitting pivotal movement of one arm of said one pair to the other arm thereof.
